RAILWAY AND TRAMWAY RAIL AND WHEEL
FLANGE LUBRICATIONEdwin George Butcher, Wahroonga, New South
Wales, and William Edmund Jupe, Eastwood,
New South Wales, AustraliaApplication December 13, 1932, Serial No. 647,030
In Australia July 11, 1932

9 Claims. (Cl. 184—3)

This invention relates to improved methods and improved means for reducing the wear of rails at curves on a railway or tramway track and of the wheel flanges of the rolling stock, due to contact of the wheel flanges with the side of the rail head, by the automatic application of small quantities of fluid lubricant to the wheel flanges before such contact occurs.

Our invention comprises the positioning of a fluid lubricant container, which functions as a distributor, parallel to and near or in contact with the inner side of a rail head in such a manner that destruction or mutilation of the container by the wheel flanges is prevented; automatic and intermittent feeding of lubricant to the container from a source of supply; the delivery of small quantities of lubricant to the exterior of the container; the removal of portion of these quantities by the wheel flanges; and the removal and collection for further use of excess deliveries of lubricant from the distributor.

In the accompanying drawing which illustrates the invention:—

Fig. 1 is a side elevation of the device positioned near a rail;

Fig. 2 is a similar view of a container and supporting springs;

Fig. 3 is a sectional end elevation of the device in Fig. 2 positioned on a rail;

Fig. 4 is an end elevation of the tongue in Fig. 3;

Fig. 5 a sectional end elevation of another form of container;

Fig. 6 is an enlarged perspective view of portion of the tongue of Fig. 5;

Fig. 7 and Fig. 8 are sectional elevations showing other forms of contact members;

Fig. 9 is a front elevation of a portion of the lower lip of the container in Fig. 7;

Fig. 10 is a similar view of the under face of the contact member of Fig. 7;

Fig. 11 is a sectional elevation of a supply tank and fittings.

A lubricant container 10, formed, preferably, of sheet metal or other stiff yet flexible material, is of approximately triangular cross section and formed with a delivery mouth near its apex, the mouth being a longitudinal slot or a series of spaced holes; the container is mounted in a metal trough 11 and resiliently supported as, for example, by steel wires 12, 12 which are adjustably secured to spring plates 13 and to suitable fixed supports 14, 14 on the track bed.

Another form of resilient mounting for the container and trough (Figs. 2 and 3) comprises leaf springs 15, 15 each secured to a steel plate 16

which is fastened to the foot of a rail by a lug 17 and a movable latch 18. The other end of each spring is secured to the trough 11 by a bolt 19 which passes through the trough and is extended to contact with the web of the rail. In this form of the invention the inner wall 20 of the trough is adapted to contact with the under face of the rail head and by adjusting the length of the wall 20 the apex of the container may be positioned as desired in relation to the inner face 21 of the rail head.

The resilient mountings of the container are so arranged and adjusted that pressure by the wheel flanges of the rolling stock forces the container and trough downwards and retains them in that position and thus prevents destruction or mutilation of the container and trough by the wheel flanges, the upper outer ends of the container being bevelled off to minimize the initial action of the first oncoming wheel flange.

The rail-side wall 22 of the container (Figs. 3, 5, 7 and 8) is extended to form a relatively fixed upper lip 23 which is outwardly turned and functions as a directing lip of the mouth for lubricant which is forced into the top of the container. The container wall 24 remote from the rail is provided with a relatively movable inwardly directed lower lip 25. These lips form a portion of the mouth of the container.

In Figs. 3, 5, and 8 the mouth of the container is fitted with a metal tongue 26 provided with means positioned in the line of travel of the wheel flanges of the rolling stock for contact therewith. The outer ends of these means are also bevelled off.

The tongue 26 (Fig. 3) is loose in the container and is provided on its lower inner face with spring fingers 26A which return the tongue to its original contacting position.

The tongue 26 (Figs. 5 and 6) is supported on the lower lip 25 and is fitted with an inwardly and upwardly directed perforated member 27, which tends to restrict the mouth of the container, and with an outwardly curved and downwardly directed movable contact member 28. This contact member 28 may be in the form of a longitudinal rod (Figs. 3 and 8), and in Fig. 7 is shown as a contact wiper which is resiliently mounted on leaf springs 29.

The tongue 26 of Fig. 8 is secured to the lower lip 25.

As shown in Fig. 7 the contact wiper 28 is positioned over the container mouth which is in the form of spaced holes 30 in the lower lip (Fig. 9). Depressions 31 and open channels 32 (Fig. 10)

are formed in the inner face of the member 28 in correspondence with the holes 30 and are adapted to be moved downwards by the wheel flanges into alignment with the holes so that lubricant 5 passes to the top of the member 28 and thence to the wheel flanges. When the wheels pass on the springs 29 automatically lift member 28 so that the holes 30 are closed and unnecessary leakage from the container is prevented while the 10 device is not being operated.

The pressure of wheel flanges on each contact member 28 forces the member inwards and downwards so that the capacity of the container near the upper end of the wall 22 or portion of this 15 capacity is reduced by the movement of the tongue 26 or by the movement of the upper portion of the wall 24 or by both movements.

Excessive upward movement of the container and trough due to the resilience of the mountings 20 is prevented by means of adjustable stops 33 fitted into fixed supports 34 on the track (Fig. 1) or to the contact of the wall 20 (Fig. 3) with the rail head.

A lubricant supply tank consists of a liquid-25 and air-tight chamber 35 provided with a filter 35A and an air sealing cap 36. By means of adjustable nuts 45 on studs 46 mounted on a bar 47 which is secured to the foot of a rail by adjustable lugs 48, the tank is mounted at a height sufficient to establish and maintain lubricant at 30 an approximately constant level in the container during the periods of inoperation of the container.

A lubricant trap 37 is secured to the tank and is fitted with an air inlet pipe 38 and a delivery-35 mouth 39 to which is attached a flexible pipe line 40 in communication with the container 10. To prevent return of lubricant from the pipe to the trap a check valve 41 may be fitted in the pipe line.

30 An aperture 41 in the partition wall at a convenient height therein serves as a means of communication between the chamber 35 and the trap 37.

The tank, trap, pipe line, and container 10 are supplied with lubricant to the desired level. 45 Passage of a wheel flange of the rolling stock into contact with member 28 produces lateral and downward pressure on the tongue 26 and or on the upper portion of the wall 24 of the container so that the capacity of the upper portion of the 50 container or that portion of the capacity lying between the tongue and the wall 22 is reduced and lubricant is thereby forced upwards and directed outwardly by the upper lip 23 on to the 55 wheel flange at its junction with the tread of the wheel. The flange thus lubricated transfers a portion of the lubricant to a wearing part 42 (Fig. 3) of a rail head at a curve in the track, thus reducing wear of the rail head and of the wheel flanges contacting therewith.

30 Excess lubricant delivered from the mouth of the container 10 is collected by the trough 11 and delivered by a pipe 43 to a collector 44 positioned at a lower level than the trough.

35 On the removal of lubricant from the container by the action of the wheel flanges further supplies, to make good the loss and to restore the level of lubricant in the container, are provided by the trap 37. Flow of lubricant from the 40 chamber 35, controlled by atmospheric pressure through the pipe 38, re-establishes the level of lubricant in the trap and, thereby, in the container 10.

We claim:

35 1. A rail and wheel-flange lubricator compris-

ing a lubricant-container of approximately triangular cross-section, a delivery-mouth near the apex of said container fitted with a relatively fixed upper directing-lip and a relatively movable lower lip, a movable tongue supported by 80 said lower lip, a contact member on said tongue, and adjustable resilient mountings adapted to position the apex of said container adjacent to the inner side of a rail-head and said contact member in the line of travel of a wheel-flange. 85

2. A rail and wheel-flange lubricator comprising a lubricant-container of approximately triangular cross-section, a delivery-mouth near the apex of said container provided with an outwardly turned upper directing-lip and an inwardly directed lower lip, a tongue mounted in said mouth fitted with an inwardly and upwardly perforated member and with an outwardly and downwardly directed contact member adapted to be positioned in the line of travel of a wheel-flange, and adjustable resilient mountings adapted to position the apex of said container adjacent to the inner side of a rail-head. 90

3. A rail and wheel-flange lubricator comprising a lubricant-container of approximately triangular cross-section, a delivery-mouth near the apex of said container fitted with an outwardly turned directing upper lip and an inwardly directed lower lip, and outwardly directed tongue secured to said lower lip, a contact member secured to the outer end of said tongue adapted to be positioned in the line of travel of a wheel-flange, and adjustable resilient mountings adapted to position the apex of said container adjacent to the inner side of a rail-head. 100

4. A rail and wheel-flange lubricator comprising a lubricant-container of approximately triangular cross-section of flexible material having a delivery-mouth near its apex, adjustable resilient mountings adapted to position the apex of 105 said container adjacent to the inner side of a rail-head, and the outer wall of said container being adapted to be moved toward the wall adjacent to the rail. 110

5. A rail and wheel-flange lubricator comprising a lubricant-container of approximately triangular cross-section, a delivery-mouth near the apex of said container, a supply-tank, a pipe connecting said tank and container, a lubricant-trap in the supply line between said tank and container, an air-inlet for said trap, and adjustable mountings adapted to position the apex of said container adjacent to the side of a rail-head. 120

6. A rail and wheel-flange lubricator comprising a lubricant-container having a delivery-mouth formed with a relatively fixed upper directing-lip and a relatively movable lower lip, a movable tongue supported by said lower lip, a contact member on said tongue adapted to be positioned in the line of travel of a wheel-flange, 130 and means adapted yieldingly to position the mouth adjacent to the side of a rail-head. 135

7. A rail and wheel-flange lubricator comprising a lubricant-container having a delivery-mouth formed with an outwardly turned upper directing lip and an inwardly directed lower lip, a tongue mounted within the mouth having an inwardly and upwardly directed perforated and an outwardly and downwardly directed contact member adapted to be positioned in the line of travel of a wheel-flange, and means adapted yieldingly to position the mouth adjacent to the side of a rail-head. 140

8. A rail and wheel-flange lubricator comprising a lubricant-container having a delivery- 145

mouth formed with an outwardly turned upper directing-lip and an inwardly directed lower lip, an outwardly directed tongue on said lower lip, a contact member on the outer portion of said tongue adapted to be positioned in the line of travel of a wheel-flange, and means adapted yieldingly to position the mouth adjacent to the side of a rail-head.

9. A rail and wheel-flange lubricator comprising a lubricant-container having upwardly-ex-

tending rail-abutting and outer walls with a delivery-mouth between the upper edges thereof, a yieldable tongue in said mouth capable of being pressed by a wheel-flange toward said rail-abutting wall whereby to squeeze lubricant from the mouth, and means for mounting said lubricator with its mouth adjacent to the side of a rail-head.
